(57) **CLAIM**

The ornamental design for a nasal cannula assembly, as
shown and described.

DESCRIPTION

FIG. 1 is a front, top and right side perspective view of a
nasal cannula assembly having a gas sampling line with a
tip, tube and clip, showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines in the drawings illustrate portions of the
nasal cannula assembly which form no part of the claimed
design.
